Specification of Letters Patent.

Patented Oct. 28, 1913.

Application filed September 8, 1910. Serial No. 581,020.

To all whom it may concern:

Be it known that we, PHILIPPE WERNER and ERNEST JUILLARD, citizens of the Confederation of Switzerland, residing in 5 Châtelaine, near Geneva, Canton of Geneva, in the Confederation of Switzerland, have jointly invented an Improvement in Automatic Electric Regulators, of which the following is a specification.

10 The subject of the present invention is an automatic electric regulator or governor which is provided with a rotary slide valve of which a part forms a differential piston, upon the surfaces of which acts in one direction a liquid which is under pressure and in the other direction a liquid which can flow through one or more openings which are controlled by a light controlling device which moves with the member which is 15 under the influence of the quantity to be regulated, for the purpose of reducing as much as possible the mass which has to be moved by the first member in order to actuate the regulator.

20 Moreover, our invention includes apparatus for preventing overregulating, and this apparatus preferably consists of two laminae, the corresponding ends of which are fixed in position. The other end of one 25 lamina is connected by means of an adjustable device with the regulating member while the other end of the other lamina is connected with the member which is under the influence of the quantity to be regulated. The laminae are connected between 30 their ends by means of a link, the position of which may be varied, in order that simultaneously with the regulation of the adjustable device, the throttling of the regulating oscillations may be regulated until 35 there is a complete suppression of these 40 oscillations.

The accompanying drawing shows by way of example a constructional form of the 45 regulator according to the present invention.

Figures 1 and 2 illustrate together a cross section and Figs. 3 and 4 a partial longitudinal section of this constructional form. 50 Fig. 5 is an elevation of the electromagnet 3. Fig. 6 is a side elevation of the laminae and associated parts. Figs. 7, 8, 9, 10 and 11 are sectional views through the lines

A—B, C—D, E—F, G—H, and I—K, of the Fig. 1. Fig. 12 is a section through 55 L—M of Fig. 11. Fig. 13 is a detail section. Fig. 14 is a section through N—O of the Fig. 4, and Fig. 15 is an elevation illustrating our improved regulator.

The embodiment of the invention shown 60 in the drawing serves to regulate the voltage of an electric central installation and for the purpose is provided on one side with a coil 1 (Fig. 3) which is movable between the limbs 2 of a three-pole electromagnet 3, as shown in Fig. 5, the coil being controlled by the system to be regulated, that is, by the voltage of the installation; on the other side the regulator is provided with a regulating mechanism in the form 65 of a rotary contact arm 4, Fig. 2, right hand side, which is adapted to connect a fixed contact ring 5 with a series of fixed contacts 6.

The coil 1 is fixed at one end of the lever 7, the movements of which are limited by stops 7' and the other end of which carries the controlling member, a rod 8, Fig. 1, with a sleeve 8'. This member actuates the slide valve 9, throttling more or less the 80 passage of a liquid such as oil, which is set under pressure by a pump 10, whereby the slide valve allows the liquid under pressure to flow into the one or other of two chambers of the driving apparatus 11, which are 85 partly separated by a rotary plate 12, which is connected with the contact arm 4, and whereby said arm is moved in one direction or the other.

The pump 10, Figs. 4 and 14, adapted for 90 supplying the liquid, is a double centrifugal pump, the rotating wheel blade or rotors 13 of which are mounted on a perpendicular shaft 14 which is driven by means of bevel wheels 15 by a shaft 16 which is provided with a pulley 17. The pump draws liquid from the lower part of a casing 18 and forces the same through its guide blades 19 and rotor wheels 13 into a collecting passage 20 from where this liquid flows into a 100 passage 21, Figs. 1 and 10. This latter passage is formed in a casing 22 which is adapted to contain the slide valve 9 and surrounds the latter which comprises an inner cylinder 23 and an outer cylinder 24. 105 The annular space 25 between both cylinders

ders is closed at its bottom by a wall 26 and at its top by an annulus 27 which is tightly adjusted on a socket 28 of the slide valve chamber. The passage 21 is connected with the space 25 by openings which are provided in the cylinder 24, and the height of the passage 21 is such that this connection always exists whatever the axial position of the slide valve 9 may be. The inner cylinder 23 extends downward beyond the outer cylinder 24 and passes snugly through a wall 30 which closes at the bottom of the slide valve chamber. The projecting end 31 of said cylinder is formed with openings 32 which connect the space 33 which is beneath the annular bottom wall 26 with the inside of the cylinder 23. This space is connected with the space 25 by an opening 34 formed in the bottom 26. A sieve-like cylinder is arranged in the space 25 around the cylinder 23, this part being adapted to prevent impurities which the liquid might contain from entering the opening 34. On the end 31 of the slide valve 9 is mounted a bow 35 (Fig. 3) which, by means of a ball 36 is pivoted freely on one arm of a lever 37, the other arm of which is provided with a sliding balance weight 38 and is arranged in a support 39 which is fixed on the wall 30.

The liquid which comes from the passage 21 under pressure flows through the openings 40 into the space 25, from there through the sieve-like part and the opening 34 into the space 33 and passes from the latter through the openings 32 to the inside of the cylinder 23, whence it can flow into the casing 18, both through openings 41 provided in the upper part of the cylinder and out of the top of the cylinder. In order to throttle the discharge of the liquid by the slide 9, for shifting the latter, the sleeve 8' of the distributing member can move in the inside of the end 31 of the slide in order to uncover or cover the openings 32 more or less. This sleeve itself is formed with openings 42 which permanently connect its interior with the casing 18 and form a second outlet for the liquid which flows out of the space 33. The rod 8 is screwed in a block 43 which is suspended from one end of the lever 7 by means of two thin steel bands 44.

The outer cylinder 24 of the slide is formed with two series of openings 45 and 46, which are situated one above the other. The one series 45 is adapted to connect the space which is full of liquid under pressure with one or other of two openings 47 and 48 which are connected by passages 49 and 50 respectively with the chambers 51 and 52 respectively of the operating device 11, while the other series 46 is arranged so that it connects an opening 53 in the passage 50 with the casing 18, when the opening 47 is connected by the openings 45 with

the space 25, and also the opening 47 with the casing 18 when the opening 48 is connected by the openings 45 with the space 25.

In order to impart a continuous rotary movement to the slide valve 9 for the purpose of reducing the friction during its sliding movements, a toothed wheel 54 is mounted on the inner cylinder 23 of the slide valve. This pinion is driven by means of an idle wheel and a pinion 56 which is keyed to the shaft 14. The idle wheel 55 is of such breadth as to remain continuously in engagement with the wheel 54, whatever the axial position of the slide valve and the wheel 54 may be. The passages 49 and 50 open into the chambers 51 and 52 of the driving device which are separated from each other by a fixed wall 57 and by the rotary plate 12. The latter carries a cylindrical segment 80, which can move along the cylindrical inner wall of the casing and effects a tight joint therewith.

The device for preventing overregulation comprises a pinion 58 which is fixed on the shaft of the rotary plate 12, and this pinion engages with a toothed sector 60 arranged on one end of the lever 61 which is freely pivoted at 62 on the cover 63 of the casing 18. The other end of the lever 61 is connected with the free end of a resilient lamina 64 by means of a part 65, which lamina is fixed at its other end to a column 66 which is arranged on the cover 63. On the column 66 one end of a second resilient lamina 67 is also fixed; this lamina 67 is twice bent at right angles and its other end is connected by means of a helical spring 68 with the arm of the lever 7, carrying the coil 1. The two laminae 64 and 67 are connected together by means of a rod 69 both the ends of which are reduced in cross section and are threaded and carry axially movable cones 70 against the points of which the laminae are pressed by means of thumb nuts 71 having conical projections, as shown in Fig. 6. Between the cones 70 is a very strong helical spring 72 surrounding the rod 69. Owing to the conical form of these parts and of the projections of the thumb nuts, the two laminae can bend with considerable freedom at their junction. Each lamina is formed with holes 73 in which the rod 69 can be placed at will in order to alter the connection between the laminae. The member 65 connecting the lever 61 with the lamina 64 consists of a cylinder 74 (Fig. 3) which is pivoted to the lever 61 and in which a piston 75 can move freely; the rod 76 of this piston is connected at its free end with the lamina 64. In this rod a channel 77 is provided which connects the two sides of the piston. The orifice at the upper end of the channel 77 may be more or less uncovered by a sleeve 78 which is slidably adjustable to position on the rod 76. The slide valve 1

chamber, the centrifugal pump 10, the wheel 54, idle wheel 55 and pinion 56, are arranged in the casing 18 which is intended to contain a liquid. In the cover 63 of this casing 5 a recess is provided in which the operating device 11 is partially arranged.

The constructional form of the regulator described above operates as follows: The voltage of the installation being normal, the lever 7 assumes the position shown in the drawing, in which position the sleeve 8' partially covers the openings 32. The liquid supplied by the centrifugal pump 10 flows through the openings 40, 34, 32, and through 15 the interior of the cylinder 23 and of the sleeve 8' back into the casing 18. The pressure of the liquid acts on one hand upon the upper surface of the wall 26 and on the other hand in the opposite direction upon 20 the lower face of the wall 26 and upon the surface of the annulus 27. At the openings 32 and 34 there are two drops of pressure, the proportion of which varies with the throttling of openings 32 by the sleeve 8' 25 the pressure in space 33 varies with said throttling. The position of the sleeve 8' is chosen that under normal voltage the slide valve 9 closes the chambers 51 and 52 of the motor device by covering the openings 46 30 and 45. When the coil 1 rises owing to a drop in the voltage of the installation, the rod 8 and the sleeve 8' descend, the latter uncovering the openings 32 to a greater extent. In the space 33, there is then a release 35 of the full pressure so that the slide valve 9 moves downward. By this means the openings 45 are connected with the openings 48 and the openings 46 with the opening 47 so that the chamber 52 receives liquid under 40 pressure, while liquid can escape from the chamber 51 into the casing 18. The contact arm 4 therefore is moved in a clockwise direction. By the rotation imparted to the contact arm 4 the cylinder 74 is quickly 45 drawn downward by means of the pinion 58 acting through the toothed sector 60 and the lever 61. The downward movement of the cylinder 74 causes the piston 75 to also move downwardly, because the liquid contained in 50 the cylinder is practically non-compressible and furthermore would not flow through the passage 77 with sufficient rapidity to permit of a movement of the cylinder 74 without a movement in the same direction 55 of the piston 75. This movement of the piston 75 causes a downward movement of the laminæ 64 and by means of the rod 69, this downward movement of the laminæ 64 is communicated to the laminæ 67. By this 60 means the spring 68 is slightly compressed and presses the coil 1 downward, that is, in a direction which is opposite to the first movement of the coil. When therefore the movement of the lever 7 does not immedi- 65 ately produce the necessary rise in the volt-

age, the devices consisting of the toothed sector 60 the lever 61, the pinion 58, the laminæ 64 and 67, prevent abnormal regulation. When on the contrary, the coil 1, owing to a rise in the voltage of the installation, is more strongly attracted by the electro-magnet 8, the sleeve 8' rises and throttles the passage of the liquid through the openings 32 to an even larger extent. By this means the openings 45 are connected with the opening 47 and the openings 46 with the opening 53, so that the chamber 51 of the operating device 11 receives liquid under pressure while liquid can flow out of the chamber 52, the contact arm 4 rotates in the counter clockwise direction, in order to produce a reduction of the voltage. The cylinder 74 is however thereby raised and the piston 75 follows the movement, so that the free ends of the laminæ 64 and 67 rise and the coil is slightly raised, in order again to prevent overregulation. In both cases, the laminæ 64 and 67 are displaced from their normal position and therefore slightly bent so that they exert a pressure upon the piston 75 the result being that the liquid in the cylinder 74 flows gradually through the channel 77 from one side of the piston to the other. The resilient laminæ therefore after a certain time has elapsed, resume their normal position.

By varying the section of the passage 77 by means of the sleeve 78, it is possible to vary the period which the laminæ take to resume their normal position. Further for 100 a given displacement upward or downward of the point of connection between the member 65 and the elastic laminæ 64 it is possible to vary the amount by which the coil 1 is moved back, by passing the rod 69 through two corresponding holes 73, which are more or less distant from the point of attachment of the laminæ 64 and 67 to the column 66. For example, when the rod 69 is passed through the holes 73 of the laminæ 110 64 and 67 as shown in Fig. 6, both the laminæ 64 and 67 are deflected to a certain extent and the coil 1 moved a certain distance when the member 65 is moved a given distance. Now if the rod 69 is placed in a 115 corresponding hole 73 in the laminæ 64 and 67, but nearer to the member 65, the same extent of movement of the member 65 causes a relatively greater movement of the upper part of the rod 69, and a relatively smaller 120 movement of that part of the laminæ 67 which lies between the rod 69 and the spring 68. The movement of the coil, therefore, in this instance is necessarily greater than when the rod 69 is in the position shown 125 in Fig. 6. On the other hand, if the rod 69 is passed through a corresponding pair of holes 73 in the laminæ nearer to the support 66, the same extent of movement of the member 65 causes a relatively smaller move- 130

ment at the upper end of the rod 69 and a correspondingly greater movement in that part of the lamina 67 which lies between the rod 69 and the spring 68, and in this instance the movement of the coil is less than when the rod 69 is in the position shown in Fig. 6. It is in this way that the coaction between the member 65 and the coil 1 may be varied.

Connection between the distributor and the electro-magnetic balance.—As the distributor offers a relatively considerable mass which would oppose the rapid movements of the electro-magnetic couple, the efforts necessary to overcome this inertia are borrowed from the oil under pressure. For that purpose the oil under pressure entering the distributor by the openings 40 maintains the space 9 under pressure. As the surface 20 of the annulus 27, which limits the space 9 is about by half smaller than the surface of the bottom 26, the pressure in the space 9 produces a vertical effort which tends to cause the distributor to sink. It is therefore necessary for maintaining the distributor in equilibrium to produce below the bottom 26, *i. e.* in the space 33 such a pressure that the effort which it will exert upon the bottom will be equal to the other effort mentioned. For that purpose the bottom 26 is provided with a small opening 34; further the space 33 communicates with the outside by the openings 32 ending in the central conduit, then from there by openings 42, on the bottom or 41 on the top. The openings 32 can be opened or closed by the sleeve 8¹ connected by means of the rod 8 to the electromagnetic balance 7. Let us suppose now that the openings 32 are completely shut by the sleeve 8¹ and that one maintains, for instance by hand, the distributor immovable. In the space 33 a pressure equal to that of the space 9 will reign, as 34 and 33 are connected together by the opening 34 and as no oil passes through 34, the distributor being motionless. But then the vertical effort produced in the space 33 is greater than the effort in the room 9 and the distributor tends to rise. The distributor being now let loose, but the openings 32 however maintained closed, the distributor according to the effort which acts upon it, will rise with a speed which depends on the size of the opening 34. Let us now suppose on the other hand, that the openings 32 are maintained open. The oil under pressure will then pass from the room 9 through 34 and transform the pressure into speed which is lost afterward by the eddy. For passing 60 from 33 to the outside through the openings 32 the same quantity of oil needs only a very much lower pressure. There will be therefore sensibly the same pressure in the inside of the space 33 as outside. The effort produced by the oil under pressure in the room

9 tends therefore to cause the distributor to sink.

It will be understood that between these two extreme cases in which the openings 32 are completely open or shut, there exists a certain partial closing of the openings, for which the pressure in the space 33 is such that it maintains the distributor in equilibrium. And when the sleeve 8¹ is somewhat displaced the distributor will displace in the same direction and will catch again in some measure the sleeve until the openings 32 are shut in an extent corresponding to the immobility of the distributor.

In the above described form of the apparatus, the member which stands under the influence of the quantity to be regulated, has by its movements to move only the light sleeve, so that the mass connected with it is reduced to a minimum. The result of it is that the apparatus is highly sensitive.

The regulation effected by the regulator or governor according to the present invention might, instead of controlling the voltage, be used to control the current, or to be employed for other analogous uses.

We claim as our invention:

1. An automatic electric governor, comprising a device variably movable under the influence of the circuit to be controlled, a controlling device, a cylindrical valve, a piston, means for supplying fluid under pressure to the interior of the said cylindrical valve to act against one side of the said piston, and means whereby a variable fluid pressure dependent upon the position of said device is exerted against the other side of the said piston, so that through variations in the said fluid pressure, the cylindrical valve is moved to open and close ports for the admission and exhaust of the fluid under pressure to passages for actuating the said controlling device.

2. An automatic electric governor comprising a device variably movable under the influence of the circuit to be controlled, a controlling device, a cylindrical valve, a piston, means for supplying fluid pressure to the interior of the said cylindrical valve to act against one side of the said piston, means whereby a variable fluid pressure dependent upon the position of said device is exerted against the other side of the said piston, so that through variations in the said fluid pressure, the cylindrical valve is moved to open and close ports for the admission and exhaust of the fluid under pressure to passages for actuating the said controlling device and means for preventing abnormal regulation.

3. An automatic electric governor comprising a device variably movable under the influence of the circuit to be controlled, a controller, a cylindrical valve, means for supplying fluid under pressure to the in-

terior of said cylindrical valve, a piston connected to said cylindrical valve and having an aperture therein through which the fluid under pressure may pass from the interior 5 of the cylindrical valve to a compartment on the opposite side of the said piston, an auxiliary valve controlling ports through which the said fluid may escape from the said compartment, the differences in pressure 10 on the opposite sides of the said piston depending upon the extent to which the said ports are open to control the movement of the said cylindrical valve, and means actuated by the fluid under pressure through the 15 movements of said cylindrical valve for operating the said controller.

4. An automatic electric governor comprising a device variably movable under the influence of the circuit to be controlled, a 20 contact device, a cylindrical valve having ports therein, means for supplying a liquid under pressure to the interior of the cylindrical valve, a piston connected to the cylindrical valve and on one side of which the 25 liquid under pressure acts, there being an aperture through the said piston through which the liquid under pressure may pass to a chamber on the other side of the piston, an auxiliary valve controlling ports through 30 which the liquid passes from the said compartment, means for connecting the said auxiliary valve to the first aforesaid device, and an operating device actuated by the liquid under pressure through the 35 movements of the said cylindrical valve to operate the said contact device.

5. An automatic electric controller comprising a device variably movable under the influence of the circuit to be controlled, a 40 contact device, a cylindrical valve having ports therein, means for supplying a liquid under pressure to the interior of the cylindrical valve, a piston connected to the cylindrical valve and on one side of which the 45 liquid under pressure acts, there being an aperture through the said piston through which the liquid under pressure may pass to a chamber on the other side of the piston, an auxiliary valve controlling ports 50 through which the liquid passes from the said compartment, means for connecting the said auxiliary valve to the first aforesaid device, a drum, a shaft connected to said contact device, a revolute piston on the 55 shaft and within the said drum, and connections from the interior of the said drum to the said cylindrical valve whereby through the movements of the said cylindrical valve the liquid under pressure is admitted and withdrawn from the said drum to actuate the rotatable piston therein and so move the said contact device, a revolute piston on the 60 shaft and within the said drum, and connections from the interior of the said drum to the said cylindrical valve whereby through the movements of the said cylindrical valve the liquid under pressure is admitted and withdrawn from the said drum to actuate the rotatable piston therein and so move the said contact device.

6. An automatic electric governor comprising a device variably movable under the 65 influence of the circuit to be controlled, a

contact device, a cylindrical valve having ports therein, means for supplying liquid under pressure to the interior of the cylindrical valve, a piston connected to the cylindrical valve and on one side of which the 70 liquid under pressure acts, there being an aperture through the said piston through which the liquid under pressure may pass to a chamber on the other side of the piston, an auxiliary valve controlling ports 75 through which the liquid passes from the said compartment, means for connecting the said auxiliary valve to the first aforesaid device, a drum, a shaft connected to said contact device, a rotatable piston on the 80 shaft and within said drum, connections from the interior of the said drum to the said cylindrical valve whereby through the movements of the said cylindrical valve the liquid under pressure is admitted and withdrawn from the said drum to actuate the rotatable piston therein and so move the said contact device, and means for imparting a continuous revolute motion to the said cylindrical valve.

7. An automatic electric governor comprising a device variably movable under the influence of the circuit to be controlled, a contact device, a cylindrical valve having ports therein, means for supplying a liquid 95 under pressure to the interior of the cylindrical valve, a piston connected to the cylindrical valve and on one side of which the liquid under pressure acts, there being an aperture through the said piston through 100 which the liquid under pressure may pass to a chamber on the other side of the piston, an auxiliary valve controlling ports through which the liquid passes from the said compartment, means for connecting the said auxiliary valve to the first aforesaid device, a drum, a shaft connected to said contact device, a rotatable piston on the shaft and within the said drum, connections from the 105 interior of the said drum to the said cylindrical valve whereby through the movements of the said cylindrical valve the liquid under pressure is admitted and withdrawn from the said drum to actuate the rotatable piston therein and so move the said contact device, means for imparting a continuous motion to the said cylindrical valve, and means for preventing abnormal regulation.

8. An automatic electric governor comprising a device variably movable under the 120 influence of the circuit to be controlled, a contact device, a cylindrical valve having ports therein, means for supplying liquid under pressure to the interior of the cylindrical valve, a piston connected to the cylindrical valve and on one side of which the 125 liquid under pressure acts, there being an aperture through the said piston through which the liquid under pressure may pass to a chamber on the other side of the piston,

an auxiliary valve controlling ports through which the liquid passes from the said compartment, means for connecting the said auxiliary valve to the first aforesaid device, a drum, a shaft connected to said contact device, a rotatable piston on the shaft and within said drum, connections from the interior of the said drum to the said cylindrical valve whereby through the movements 10 of the said cylindrical valve the liquid under pressure is admitted and withdrawn from the said drum to actuate the rotatable piston therein and so move the said contact device, means for imparting a continuous revolu- 15 lable motion to the said cylindrical valve and means actuated from and by the shaft in the said drum for imparting to the first aforesaid device movements in the opposite directions from those imparted thereto by 20 the influence of the circuit to be controlled.

9. An automatic electric governor comprising a device variably movable under the influence of the circuit to be controlled, a contact device, a cylindrical valve having 25 ports therein, means for supplying liquid under pressure to the interior of the cylindrical valve, a piston connected to the cylindrical valve and on one side of which the liquid under pressure acts, there being an 30 aperture through the said piston through which the liquid under pressure may pass to a chamber on the other side of the piston, an auxiliary valve controlling ports through

which the liquid passes from the said compartment, means for connecting the said auxiliary valve to the first aforesaid device, 35 a drum, a shaft connected to said contact device, a rotatable piston on the shaft and within the said drum, connections from the interior of the said drum to the said cylindrical valve whereby through the movements of the said cylindrical valve the liquid under pressure is admitted and withdrawn from the said drum to actuate the rotatable piston therein and so move the said contact 40 device, means for imparting a continuous revoluble motion to the said cylindrical valve, a lever actuated by the shaft in the said drum, a plunger pivotally connected to the said lever, adjustable yielding devices, 45 a standard to which the corresponding ends of the said adjustable yielding devices are secured, the opposite end of one of the said adjustable yielding devices being connected to the said plunger, and a spring extending between and connecting the opposite end of the other of the said adjustable yielding devices with the first aforesaid device.

In testimony whereof we affix our signatures in presence of two witnesses.
